(57) **CLAIM**

The ornamental design for a game controller stand, as shown and described.

DESCRIPTION

FIG. 1 is a top perspective view for a game controller stand showing my new design;

FIG. 2 is a top perspective view with the face plate displaced thereof;

FIG. 3 is a left side elevation view, the right-side elevation view being a mirror image thereof;

FIG. 4 is a left side elevation view with the face place displaced, the right-side elevation view being a mirror image thereof;

FIG. 5 is a front elevation view thereof;

FIG. 6 is a front elevation view sectional view taken along lines 6-6 from FIG. 4 thereof.

FIG. 7 is a bottom view thereof;

FIG. 8 is a bottom view with the face place displaced thereof;

FIG. 9 is a top plan view thereof;

FIG. 10 is a top plan view with the face place displaced thereof;

FIG. 11 is a right-side sectional view taken along lines 11-11 from FIG. 5 thereof.

FIG. 12 is a rear elevation view thereof; and,

FIG. 13 is a bottom rear perspective view with the face plate displaced.

The broken lines in the FIGS. 1-4, 9, 10, 12 and 13 form no part of the claimed design.

1 Claim, 8 Drawing Sheets
